UNITED STATES PATENT OFFICE

2,307,606

FREEZING TRAY

Carl H. Steenstrup, Schenectady, N. Y., assignor
to General Electric Company, a corporation of
New York

Application February 21, 1939, Serial No. 257,636

6 Claims. (Cl. 62—108.5)

My invention relates to freezing trays of the type having partition elements or a grid assembly arranged to facilitate the removal of ice cubes or blocks without thawing and constitutes an improvement over the invention disclosed and claimed in my copending application Serial No. 147,056, filed June 8, 1937, now Patent No. 2,265,705, and assigned to the same assignee as my present invention.

It is an object of my invention to provide a partition assembly for freezing trays comprising a plurality of similar partition elements forming a plurality of walls of ice block compartments and an improved arrangement for retaining the partition elements in assembled relation and for accommodating relative movements between the partition elements to facilitate the release of the ice blocks therefrom.

Another object of my invention is to provide a partition assembly for freezing trays comprising a plurality of similar partition elements and an improved arrangement of a plurality of ice block compartment walls on each of said elements so arranged as to facilitate the release of the ice blocks therefrom.

A further object of my invention is to provide a freezing tray and a partition assembly therefor including an improved arrangement for facilitating the initial breaking loose and removal of ice blocks from the tray and partition walls.

Further objects and advantages of my invention will become apparent as the following description proceeds, and the features of novelty which characterize my invention will be pointed out with particularity in the claims annexed to and forming a part of this specification.

For a better understanding of my invention, reference may be had to the accompanying drawing in which Fig. 1 is a perspective view of an ice tray and partition assembly embodying my invention; Fig. 2 is a view of a portion of the grid assembly shown in Fig. 1 removed from the tray and with the several parts of one of the partition elements shown prior to assembly; Fig. 3 is a longitudinal sectional elevation of a portion of the tray shown in Fig. 1 showing an ice block being removed from the first compartment thereof; and Fig. 4 is a view similar to Fig. 2 showing a modified arrangement of my invention.

Referring now to the drawing, I have shown an elongated freezing tray 10 provided with a partition assembly comprising a plurality of similar T-shaped partition elements 11 arranged in juxtaposed relation. Each of the partition elements 11 comprises a transverse dividing wall 12 and a

longitudinal dividing wall 13 secured thereto and extending from one side thereof, the longitudinal walls of the several partition elements extending in the same direction and in substantial alignment. The longitudinal wall of the partition element at the front end of the tray and designated 13a is shaped somewhat differently from the remaining longitudinal walls as shown in Fig. 3. As clearly shown in Fig. 2, the elements 11 are secured together by a pivotal connection between the longitudinal walls 13 and 13a thereof. Each of the walls 13 is provided with a projecting portion 14 arranged to extend through a slot or other suitable opening 15 in the upper portion of the wall 12. Obviously the portion 14 of the element 13 at the rear may be omitted as it is not required for the joining of any further elements to the grid assembly. Lugs 16 and 17 may be provided on the longitudinal elements 13 and arranged to project through the lower portion of the slot 15 and an opening 18 respectively, and to be peened over to provide a rigid connection between the transverse wall 12 and the longitudinal wall 13. Flanges 19 are provided at the tops of the transverse partition walls so that a lifting force may be exerted between the top of the ice blocks in the compartment and the partition elements. In order to secure the partition elements in assembled relation, I provide pins 20 secured in holes 21 in the projections 14. Each pin engages a slot 22 in the upper portion of the end of the wall 13 of the adjacent partition element. The pins 20 are arranged to slide freely in the slots 22 and therefore provide pivotal connections and also afford limited relative vertical movements between the partition elements. Openings or notches 23 and 24 are provided at the bottom and sides, respectively, of the walls 13 so that water flowing into the tray may flow between the compartments defined by the walls.

In Fig. 3 I have shown a longitudinal sectional view of the tray and partition assembly with ice blocks 25, 26 and 27 in the compartments. When it is desired to remove an ice block from the compartment, a lifting tool or lever 28 having a curved portion 29 is placed with its end against the lower side of the flange 19 and the lever is pressed downwardly so that the curved portion 29 bears against the ice block in the compartment formed by the partition element. When the pressure is exerted between the ice block and the flange 19 the ice is sheared from the walls of the partition element and the transverse wall 12 is also sheared free from the ice in the adjoining ice block compartment. At the instant that relative

movement takes place between the ice block and the transverse wall, a small flange 30 formed along the lower edge of the transverse wall exerts a force on the ice block, tending to move it along the tray 10 and breaking the bond between the ice block and the tray. After the pair of ice blocks secured to any one of the partition elements 11 have been broken loose, they may readily be removed by rotating the partition element about its pivot pin 20. The ice blocks may be removed from the tray a pair at a time from one end to the other beginning as shown in Fig. 3. It will be noted that the longitudinal wall 13a is provided with an arcuate edge having a radius about the pivot pin 20 and the end of the tray 10 has a curvature conforming thereto. This curvature of the wall 13a and tray 10 facilitates the rotation of the end partition element and the removal of the first pair of ice blocks. In Fig. 3 the ice block 27 in the end compartment has been shown just after it has been broken loose from the walls of the partition element and from the tray and is ready to be removed from the tray by rotation of the partition element.

The construction shown in Fig. 4 is similar to that shown in Figs. 1 to 3 inclusive and includes an arrangement such that each partition element provides three or more ice blocks. Each of the partition elements shown in Fig. 4 comprises a transverse dividing wall 13, a pair of longitudinal dividing walls 32 spaced apart and having projections 33 arranged to extend through slots or openings 34 in the transverse wall 31 and to be secured to the transverse wall thereby. A third longitudinal wall 35 may be secured to the transverse wall between the walls 32 when it is desired to provide a greater number of ice block compartments. The wall 35 is preferably provided with lugs 36 arranged to extend through slots 37 in the transverse wall and to be peened over to secure the wall 35 rigidly in place.

The openings 34 are arranged in the same position in all of the transverse walls 31 and the slots 34 of the several transverse walls are arranged in alignment in two rows, one on either side of the center line of the partition assembly. The two sets of walls 32 are arranged in alignment in a manner similar to the arrangement of the walls 13 in Fig. 1, the projections 33 extending through the aligned slots 34 and serving to connect the two longitudinal walls to the transverse wall associated therewith. It will be noted that all the projections 33 are arranged on the inner side of the walls of the adjacent partition elements to which they are pivoted. It will be evident, therefore, that the walls 32 of each element diverge and are spaced farther apart at their outer ends than at their ends secured to the transverse wall 31. This arrangement facilitates the removal of ice from the inner compartment between the walls 32 of each element. Obviously a compartment or shelf formed by one of the walls 32 and the wall 35 also increases in width away from the transverse wall 31. The operation of the partition assembly shown in Fig. 4 is similar to that of the assembly shown in Figs. 1 to 3 inclusive, it being understood that the longitudinal walls in the end compartment correspond to the wall 13a in Figs. 1 to 3 and may be constructed with an arcuate form to conform to the contour of the end of the tray 10.

From the foregoing, it is readily apparent that I have provided an ice tray having a partition assembly comprising a plurality of sepa-

rately movable partition elements and including an improved arrangement for connecting the elements in assembled relation and for affording limited relative movement between the elements.

While I have described my invention in connection with a freezing tray for household refrigerators, other applications will readily be apparent to those skilled in the art. I do not, therefore, desire my invention to be limited to the particular construction shown and described and I intend in the accompanying claims to cover all embodiments within the spirit and scope of my invention.

What I claim as new and desire to secure by Letters Patent of the United States, is:

1. A removable partition assembly for freezing trays comprising a plurality of similar partition elements adapted to form walls of a plurality of ice block compartments, each of said partition elements including a transverse dividing wall having an opening in the upper portion thereof and a longitudinal dividing wall extending from one side of said transverse wall, the longitudinal wall of each of said elements having a portion projecting through the opening in the transverse wall thereof, said partition elements being arranged in juxtaposed relation with said longitudinal dividing walls extending in the same direction and in substantial alignment, and means pivotally connecting said projecting portion of each of a plurality of said longitudinal walls to a respective adjacent one of said partition elements for retaining said partition elements in assembled relation, said pivotal connecting means also providing for limited relative vertical movement between said partition elements to facilitate the release of ice blocks from said walls.

2. A removable partition assembly for freezing trays comprising a plurality of similar partition elements adapted to form walls of a plurality of ice block compartments, each of said partition elements including a transverse dividing wall having an opening in the upper portion thereof and a longitudinal dividing wall extending from one side of said transverse dividing wall and having a portion projecting from the other side of said transverse wall through the opening therein, said partition elements being arranged in juxtaposed relation with said longitudinal dividing walls extending in the same direction and in substantial alignment, and pivotal connecting means arranged to secure the projecting portion of each of a plurality of said longitudinal walls to the longitudinal wall of a respective adjacent partition element for retaining said partition elements in assembled relation, said pivotal connecting means also providing for limited relative vertical movement between said partition elements to facilitate the release of ice blocks from said walls.

3. A removable partition assembly for freezing trays comprising a plurality of similar partition elements adapted to form walls of a plurality of ice block compartments, each of said partition elements including a transverse dividing wall having an opening in the upper portion thereof and a longitudinal dividing wall extending from one side of said transverse dividing wall, each of said longitudinal dividing walls having a slot therein in the upper portion thereof remote from the transverse dividing wall from which it extends and a projection at the other end thereof extending through the opening in said transverse wall, said partition elements being arranged in juxtaposed relation with said longitudinal dividing walls, the longitudinal dividing wall of each of said elements having a portion projecting through the slot in the longitudinal dividing wall of an adjacent element, and means pivotally connecting the longitudinal dividing wall of each of a plurality of said elements to the longitudinal dividing wall of a respective adjacent element for retaining said partition elements in assembled relation, said pivotal connecting means also providing for limited relative vertical movement between said partition elements to facilitate the release of ice blocks from said walls.

75 said partition elements being arranged in juxtaposed relation with said longitudinal dividing walls.

posed relation with said longitudinal dividing walls extending in the same direction and in substantial alignment, and means including pins passing through the slots in a plurality of said longitudinal walls and engaging the projections on respective adjacent longitudinal walls for pivotally connecting said partition elements and for retaining said partition elements in assembled relation, said pins and slots providing for limited relative vertical movement between said partition elements to facilitate the release of ice blocks from said walls.

4. A removable partition assembly for freezing trays comprising a plurality of similar partition elements adapted to form walls of a plurality of ice block compartments, each of said partition elements including a transverse dividing wall having a pair of spaced apart openings in the upper portion thereof and a pair of longitudinal dividing walls extending from one side of said transverse wall and one adjacent each of said openings, each of said longitudinal walls having a portion projecting through the respective adjacent opening in said transverse wall of the partition element, said partition elements being arranged in juxtaposed relation with said pairs of openings in longitudinal alignment, and means pivotally connecting said projecting portions of each of a plurality of said longitudinal walls to the longitudinal walls of respective adjacent partition elements for retaining said partition elements in assembled relation, said projecting portions of each of said longitudinal walls being arranged transversely on the inside of the longitudinal walls of adjacent partition elements pivoted thereto whereby the walls comprising said pairs of longitudinal walls of each of said elements diverge from each other away from the transverse wall from which they extend.

5. A removable partition assembly for freezing trays comprising a plurality of similar partition elements adapted to form walls of a plurality of ice block compartments, each of said partition elements including a transverse dividing wall having a pair of spaced apart openings in the upper portion thereof and a pair of longitudinal dividing walls extending from one side of said transverse wall and one adjacent each of said openings, each of said longitudinal walls having a portion projecting through the respective adjacent opening in said transverse wall of the partition element, said partition elements being arranged in juxtaposed relation with said pairs of openings in longitudinal alignment, and means

- 5 pivotally connecting said projecting portions of each of a plurality of said longitudinal walls to the longitudinal walls of respective adjacent partition elements for retaining said partition elements in assembled relation, said projecting portions of each of said longitudinal walls being arranged transversely on the inside of the longitudinal walls of adjacent partition elements pivoted thereto whereby the walls comprising said pairs of longitudinal walls of each of said elements diverge from each other away from the transverse wall from which they extend, each of said partition elements including a third longitudinal wall secured to the transverse wall thereof and substantially co-extensive with said pair of longitudinal walls for dividing the central compartment formed by said pair of walls, said third walls of said elements being arranged in 10 longitudinal alignment.
- 15 6. In combination, a freezing tray and a removable partition assembly therefor comprising a plurality of similar partition elements adapted to form walls of a plurality of ice block compartments, each of said partition elements including a transverse dividing wall having an opening in the upper portion thereof and a longitudinal dividing wall extending from one side of said transverse wall, each of said longitudinal walls having 20 a portion projecting through the opening in one of said transverse walls, said partition elements being arranged in juxtaposed relation with said longitudinal dividing walls extending in the same direction and in substantial alignment, and 25 means pivotally connecting said projecting portion of each of a plurality of said longitudinal walls to a respective adjacent one of said partition elements for retaining said partition elements in assembled relation, said pivotal connecting means also providing for limited relative vertical movement between said partition elements to facilitate the release of ice blocks from said walls, the longitudinal wall of the partition element adjacent one end of said tray having 30 an arcuate outline having a radius substantially about the pivot point of said element on the element adjacent thereto, the end of said tray having an arcuate cross-section conforming to the curve of said arcuate longitudinal wall whereby said element at said one end of said tray may readily be rotated from its position within said tray.

CARL H. STEENSTRUP.
